UNITED STATES PATENT OFFICE.

GODFREY STIBBE, OF LEICESTER, ENGLAND.

DIAL AND CYLINDER KNITTING-MACHINE.

1,388,781.

Specification of Letters Patent. Patented Aug. 23, 1921.

Application filed November 19, 1919. Serial No. 339,169.

To all whom it may concern:

Be it known that I, GODFREY STIBBE, subject of the King of Great Britain, residing at Leicester, in the county of Leicester, England, have invented certain new and useful Improvements in or Relating to Dial and Cylinder Knitting-Machines, of which the following is a specification, reference being had therein to the accompanying drawing.

10 This invention relates to circular knitting machines and concerns machines having two sets of needles and two or more feeders.

This invention has for its object the provision of a machine for making the knitted fabric described in my United States patent application Serial No. 308,916 which fabric consists of two independently knitted webs or walls one overlying the other and united at intervals by tying or binding loops of a 15 yarn which is additional to the yarns of which said webs are formed. This fabric may also have combined with it a rib fabric said fabrics being continuous, and further a restraining yarn may be incorporated with 20 the fabric between its walls.

The present invention consists of a circular knitting machine having two sets of needles, for example cylinder and dial needles, and two or more feeders, arranged 25 so that at one or more feeders yarn is fed to the dial needles only and at another feeder or other feeders yarn is fed to the cylinder needles only whereby the two sets of needles knit independently of each other and produce 30 individual webs, and means to feed in an additional yarn so that it becomes incorporated with the loops of the two independently knitted webs and ties them together.

The additional yarn is fed in at a suitable 35 point so that it is taken by all the dial needles and drawn around the stems of the cylinder needles above the old loops thereon and below the latches. During the subsequent operation the binding yarn is 40 knocked over with the old loops on the cylinder needles and is also knocked over with the loops of the dial needles so that it becomes incorporated with the loops of the two independently knitted webs and ties 45 them together without however appearing on the face of either web or having any detrimental effect thereon.

In the method just described, the binding 50 yarn is laid on the needles of each set between the old loops and the hook but the needle hooks do not engage said yarn to

draw loops of same the binding yarn being simply knocked over with the old loops. The result of this is that the binding yarn is not knitted into either web, that is to say 60 it is not formed into stitches or loops but merely passes around the knit loops of the webs.

The machine is provided at appropriate feeders with needle actuating cams which 65 are adjustable so that the needles can be caused to take yarn or miss it as required for a purpose hereinafter described.

In particularly describing the invention reference will be made to the accompanying 70 drawing wherein, by way of example, an embodiment is shown as applied to a circular knitting machine having eight feeders.

In the drawing:—

Figure 1 is a development or straightened 75 elevation showing a succession of three feeders.

Fig. 2 is a diagrammatical plan illustrating the knitting operation at the different feeders around the machine.

Fig. 3 is a plan of the adjustable dial cam.

Fig. 4 is an elevation of the adjustable cylinder cam.

Fig. 5, is a diagrammatical view, representing in plan the double fabric the machine is designed and arranged to produce,

Fig. 6, is a perspective view or elevation of said fabric.

Figs. 5 and 6 represent the fabric in a magnified and somewhat stretched form to 90 clearly illustrate the loop formation.

Referring to Figs. 5 and 6, the two independent plain fabrics are represented by the loops *a*, and *b*, the fabric *a*, being that which is produced for example on the cylinder needles of the machine while the fabric *b*, is the one produced for example on the dial needles. The binding yarn, which is additional to the fabrics *a* and *b*, is represented at *c*. The restraining yarn is shown 95 at *d*, this being a straight non-knitted yarn at *d*, which is laid in between the two fabrics *a* and *b* and serves to prevent or limit the elasticity or stretch of the double fabric in a lateral direction.

100 Looking along Fig. 5, from the left hand end the method of producing the fabric will be readily followed, the part *e* showing the independent fabrics *a* and *b* disposed back to back, the part *f* showing the introduction 110 of the binding yarn *c*, the part *g* showing the binding yarn *c* knocked over with the

loops of the fabric *a*, the part *h* showing the introduction of the restraining yarn *d* and the binding yarn *c* knocked over with loops of the fabric *b*, and the right hand end 5 showing the commencement of the process again as at part *f*. In Fig. 6, the top course *i* shows the independent walls of fabrics *a* and *b*, the next two courses *j* show the connection of the said walls by the binding 10 yarn *c*, the next two courses *k* show the connected walls and the restraining yarn laid in, while the two lower courses *l* show the combination of a rib fabric with the double 15 fabric.

15 In the fabric illustrated in Figs. 5 and 6, it will be seen that the walls *a* and *b* are quite independently formed and are united by the yarn *c* which is incorporated with said walls without being made into stitches 20 and without appearing upon the outer face of either of the webs *a*, *b*.

The circular knitting machine forming the subject of the present invention and designed for producing the double fabric just 25 described, is equipped with cylinder needles 1 (Fig. 1) and dial needles 2 these being of the latch type and mounted to slide in needle beds in the customary manner. The needles travel in the direction indicated by 30 the arrows in the drawing, and in general construction and operation the machine may be as usual except as regards the provision made according to this invention for producing 35 fabric of the kind referred to.

35 The eight feeders of the machine are indicated in Fig. 2 at A, B, C, D, E, F, G, H, of which the feeders A, B and C are also shown in elevation in Fig. 1. The feeders and needle operating cams are so arranged 40 that at A, C, E, and G yarn is fed at 3 and knitted by the dial needles 2 only. The projection and retraction of the dial needles is represented by the dotted line in Fig. 2. At the feeders B, D, F, and H, yarn is fed at 45 4 and knitted by the cylinder needles only. Thus arranged the machine will produce two independent plain tubular webs one overlying the other and disposed back to back as is already known. At each feeder B, D, F, H 50 I provide an additional yarn feed 5 which supplies a supplementary yarn 6 (Fig. 1) to the dial needle 2 which although not receiving a knitting yarn here are projected outward and receive the supplementary 55 yarn 6 which as the dial needles are retracted is taken and held by the hooks of the dial needles and drawn around the stems of the cylinder needles 1 which at this time are, as shown, raised to clearing position. As the 60 cylinder needles move down to knock over their loops the yarn 6 is as aforesaid knocked over with said loops. Whereas at the feeders A, C, E, and G, the dial needles 2 receive a knitting yarn 3 and the cylinder needles 65 1 do not knit, the latter remain below the

dial needles as shown in Fig. 1 and the dial needles are projected in the usual way to clear their old loops and also the binding 70 yarn 6 and here they take the knitting thread 3 and knock over said binding yarn with the old loops. Referring to Figs. 1 and 2, the complete operation is that at 7 (feeders A, C, E, G,) the dial needles are projected to clear, at 8 they are retracted and take and knit the yarn 3 from feed 9, at 10 (feeders 75 B, D, F and H) the dial needles are advanced but do not clear, at 5 the dial needles take the binding yarn 6, and at 11 the dial needles are retracted drawing the binding yarn around the stems of the cylinder needles 1 80 before said cylinder needles take the yarn 4 and knit at the feed 12.

Obviously if a binding yarn 6 is fed to the dial needles 2 at each of the feeders B, D, F, H the two webs will be tied together 85 by said yarn at each course, but where in a machine arranged as described, the binding yarn is fed at a less number of the feeders the webs will be connected at a correspondingly less number of courses. This feature 90 however admits of variation as it will be manifest that in a machine having a comparatively large number of feeders, such as eight or more, the connection between the two independently knitted webs formed by 95 the course of binding yarn 6 may be widely distributed if desired by supplying said yarn to a lesser number of feeders. For general purposes it is found best to supply a binding yarn to each cylinder feeder, such 100 as B, D, and so on, so that said yarn is introduced into the fabric at each course.

When in the production of the fabric referred to, a restraining yarn is to be incorporated, this is introduced at a suitable 105 point between the knitting of the dial course and the knitting of the following cylinder course. For instance a restraining yarn 13 (Fig. 1) may be laid between the cylinder and dial needles 1 and 2 by a feed 14 positioned between the feeders B and C and arranged so that it lays its yarn between the needles 1 and 2 which yarn is wrapped around the cylinder until at the next cylinder feeder D where at or about the time 110 when the cylinder needles are rising and the dial needles are moving outward, it is introduced and becomes incorporated into the fabric being covered by the intermediate lengths of the yarn 6 which bind the two 115 knitted webs together. It will be understood that the restraining yarn 13 is not formed into loops or knitted but is simply laid in between the walls of the fabric and likewise between the courses of binding 120 yarn. While it is preferable to introduce a restraining yarn such as 13 at every course, in which case feeds similar to 14 are provided between the feeders D and E, F and G, H and A as shown in Fig. 2, such yarn 125 130

may be introduced at greater intervals by providing a less number of the feeders 14.

For the purpose of changing from knitting the double fabric to knitting a ribbed fabric in continuation thereof and vice versa, I may conveniently provide at the feeders A, C, E and G, adjustable cylinder needle cams and at the other feeders B, D, F, and H adjustable dial needle cams so that at the said feeders, the said needles may be caused to knit or not as desired. For instance at the feeders A, C, E, G, where during the knitting of the double fabric the dial needles only take the yarn 3, an adjustable up-throw cam such as 15 (Fig. 4) may be fitted. When occupying the low position, shown by dotted lines, the cam 15 allows the cylinder needles 1 to pass the said feeders at the lowest level shown in Fig. 1 so that they miss the thread 3. In the high position shown by full lines the cam raises the cylinder needles at the said feeders so that the yarn 3 is taken by these needles as well as by the dial needles 2 and as they pass under the stitch cam 16 the yarn is knitted, the two sets of needles conjointly forming a rib stitch.

Similarly at the feeders B, D, F and H where during the knitting of the double fabric the cylinder needles only take the yarn 4, an adjustable out-throw cam such as 17 (Fig. 3) may be provided. This cam is mounted to turn on a pivot 18 and the withdrawing cam 19 is similarly mounted on a pivot 20 and is connected with the cam 17 by means of a link 21 so that when the out-throw cam is adjusted the cam 19 will move in company with it. When the cams 17 and 19 are in the dotted line position the dial needles are not projected far enough to clear and moreover they are, as already stated, withdrawn so that they do not take the yarn 4. When however the cams 17 and 19 occupy the full line position the dial needles are projected to clear and also take the yarn 4 so that they coöperate with the cylinder needles at these feeders and produce ribbed fabric.

To change double fabric knitting to rib knitting and vice versa the adjustable cams 15 and 17 may be moved automatically by any suitable arrangement of mechanism operable by or from the pattern mechanism of the machine, and suitable yarn feeding or trapping devices may be employed for or in connection with the binding yarn 6 and restraining yarn 13 so that the feeding of either or both of these yarns may be automatically stopped when rib fabric is being produced and in order that said yarn or yarns may be automatically re-introduced when change is made to double fabric knitting. Such yarn feeding or trapping devices may be operated by suitable connections by or from the pattern mechanism.

To enable a selvage to be produced on the double fabric I may provide in the machine hereinbefore described, means for automatically forming a clearing course. This clearing course may be made in the usual manner viz:—by raising all the cylinder needles at a suitable point so that their latches are brought above the loops after which said needles are immediately brought down thus clearing off the loops. For this purpose a needle raising and a needle lowering cam are used, for example cams such as 15 and 16, the needle raising cam being movable to and away from its operative position by suitable automatic means. These clearing cams may be arranged between the feeders A and B or between any other similar pair of feeders such as C and D, E and F, or G and H. The above mentioned action of the cylinder needles produces a clearing course in the fabric which may be cut through to leave a neat selvage edge.

What I claim then is:—

1. A circular knitting machine having two sets of needles, two or more feeders arranged so that at one or more feeders yarn is fed to the needles of one set only and at another feeder or feeders yarn is fed to the needles of the other set only whereby the two sets of needles knit independently of each other and produce individual webs, and means to feed in an additional yarn so that it becomes passed around the bases of the loops of the individual webs wholly below the surfaces of said webs and runs from one web to the other to tie them together.

2. A circular knitting machine having cylinder needles and dial needles, two or more feeders arranged so that at one or more feeders yarn is fed to the dial needles only and at another feeder or feeders yarn is fed to the cylinder needles only whereby the two sets of needles knit independently of each other and produce individual webs, and means to feed in an additional yarn in such a manner that it is taken by the dial needles without being knitted and is drawn around the stems of the cylinder needles and is subsequently knocked over in company with the old loops on the cylinder needles and also with the old loops on the dial needles thereby becoming passed around the bases of the loops of the individual webs wholly below the exposed surfaces of said webs and running from one web to the other to tie them together, substantially as described.

3. A circular knitting machine having cylinder needles and dial needles, two or more feeders arranged so that at one or more feeders yarn is fed to the dial needles only and at another feeder or feeders yarn is fed to the cylinder needles only whereby the two sets of needles knit independently of each other and produce individual webs, means to

- feed in an additional yarn so that it becomes passed around the bases of the loops of the individual webs wholly below the exposed surfaces of said webs and runs from 5 one web to the other to tie them together, and a supplementary yarn feeder arranged to lay a restraining yarn between the dial and cylinder needles, substantially as and for the purpose described.
- 10 4. A circular knitting machine having cylinder needles and dial needles, two or more feeders arranged so that at one or more feeders yarn is fed to the dial needles only and at another feeder or feeders yarn is fed 15 to the cylinder needles only whereby the two sets of needles knit independently of each other and produce individual webs, means to feed in an additional yarn so that it becomes passed around the bases of the 20 loops of the individual webs wholly below the exposed surfaces of said webs and runs from one web to the other to tie them together, adjustable needle actuating cams at appropriate feeders, and means to automatically adjust said cams so that the needles 25 can be caused to take yarn or miss it as required for the purpose of changing from knitting double fabric to knitting ribbed fabric, substantially as described.
- 30 5. A circular knitting machine having cylinder needles and dial needles, yarn feeders arranged to feed yarn separately to the two sets of needles so that they knit independently of each other and produce individual 35 webs, means to feed an additional yarn so that it becomes passed around the bases of the loops of the individual webs wholly below the exposed surfaces of said webs and runs from one web to the other to tie them 40 together, adjustable needle actuating cams at appropriate feeders comprising an out-throw cam to regulate the movement of the dial needles and an up-throw cam to regulate the movement of the cylinder needles, and means to automatically adjust said cams so that the needles 45 can be caused to take yarn or miss it as required for the purpose of changing from knitting double fabric to knitting ribbed fabric, substantially as described.
- 50 6. A circular knitting machine having cylinder needles and dial needles, yarn feeders arranged to feed yarn separately to the two sets of needles so that they knit independently of each other and produce individual 55 webs, adjustable needle actuating cams at appropriate feeders comprising an out-throw cam to regulate the movement of the dial needles and an up-throw cam to regulate the movement of the cylinder needles, means to 60 automatically adjust said cams so that the needles can be caused to take yarn or miss it as required for the purpose of changing from knitting double fabric to knitting ribbed fabric, means to feed an additional 65 yarn so that it becomes passed around the bases of the loops of the individual webs wholly below the exposed surfaces of said webs and runs from one web to the other to tie them together, and means for automatically withholding said additional yarn when ribbed fabric is to be produced and for reintroducing said additional yarn when double fabric is to be produced, substantially as described.
7. A circular knitting machine having cylinder needles and dial needles, yarn feeders arranged to feed yarn separately to the two sets of needles so that they knit independently of each other and produce individual webs, adjustable needle actuating 75 cams at appropriate feeders comprising an out-throw cam to regulate the movement of the dial needles and an up-throw cam to regulate the movement of the cylinder needles, means to automatically adjust said cams 80 so that the needles can be caused to take yarn or miss it as required for the purpose of changing from knitting double fabric to knitting ribbed fabric, means to feed an additional yarn so that it becomes passed around the bases of the loops of the individual webs wholly below the exposed surfaces of said webs and runs from one web to the other to tie them together, a 85 supplementary yarn feeder arranged to lay a restraining yarn between the dial and cylinder needles, and means for automatically withholding and withdrawing said additional and restraining yarns when ribbed fabric is to be produced and for reintroducing and feeding said yarns when double fabric is to be produced, substantially as described.
- 90 8. A circular knitting machine having cylinder needles and dial needles, yarn feeders, adjustable cams in the vicinity of said feeders to regulate the movement of the needles, means to automatically adjust said cams so that they cause the cylinder needles and dial needles to either take yarn separately and thereby knit independently of each other and produce individual webs, or coöperate with each other and thereby produce ribbed fabric, means to feed an additional yarn so that it becomes passed 95 around the bases of the loops of the individual webs wholly below the exposed surfaces of said webs and runs from one web to the other to tie them together, means for withholding said additional yarn during 100 the knitting of ribbed fabric, and means for automatically forming a clearing course, substantially as described.
- 105 9. A circular knitting machine having cylinder needles and dial needles, yarn feeders, adjustable cams in the vicinity of said feeders to regulate the movement of the needles, means to automatically adjust said cams so that they cause the cylinder needles and dial needles to either take yarn sepa- 110 115 120 125 130

- rately and thereby knit independently of each other and produce individual webs, or coöperate with each other and thereby produce ribbed fabric, means to feed an additional yarn so that it becomes passed around the bases of the loops of the individual webs wholly below the exposed surfaces of said webs and runs from one web to the other to tie them together, means for withholding said additional yarn during the knitting of ribbed fabric, a needle raising cam and a needle lowering cam adapted to operate the cylinder needles for forming a clearing course, and means for putting said cams into and out of operation automatically, substantially as described.
10. A circular multiple feeder knitting machine having cylinder needles and dial needles, cams for causing the cylinder needles and dial needles to take yarn and knit at different feeders whereby they produce independent webs, means for automatically adjusting said cams for causing said cylinder needles and dial needles to knit 25 in coöperation at the same feeders whereby they produce ribbed fabric, automatically controlled means for feeding during production of double fabric an additional yarn so that it becomes passed around the bases of the loops of the individual webs wholly below the exposed surfaces of said webs and runs from one web to the other to tie them together, said means withholding said yarn during the production of ribbed fabric, means for laying a supplementary yarn 30 between the two sets of needles during the production of double fabric, and withdrawing said yarn during the production of ribbed fabric, cams for raising and lowering the cylinder needles to form a clearing 35 course, and means operating automatically for moving said raising and lowering cams to and from the operative position substantially as described.
11. In testimony whereof I affix my signature 40 in presence of two witnesses.
